UNITED STATES PATENT OFFICE.

CARL G. GROSS, OF MOUNT VERNON, NEW YORK, ASSIGNOR TO EASTERN LABORATORIES, INC., OF NEW YORK, N. Y.

DESIGN FOR A COMBINED CASING AND SUPPORT FOR ELECTRIC HAIR-DRYING MACHINES.

Application filed October 30, 1924. Serial No. 11,232. Term of patent 14 years.

To all whom it may concern:

Be it known that I, CARL G. Gross, a citizen of the United States, at present residing at the city of Mount Vernon, county of Westchester, State of New York, have invented a new, original, and ornamental Design for a Combined Casing and Support for Electric Hair-Drying Machines, for which the following is a specification, reference being had to the accompanying drawing, forming part thereof.

The figure in the drawing is a three quarter side view of the machine embodying my invention.

I claim:

The ornamental design for a combined casing and support for electric hair drying machines, as shown.

CARL G. GROSS.
